DESIGN FOR A COMBINED ASH TRAY AND HUMIDOR

Hamilton O. Cornwall, Pelham Manor, N. Y.

Application October 5, 1945, Serial No. 122,550

Term of patent 3½ years

(Cl. D85—2)

To all whom it may concern:

Be it known that I, Hamilton O. Cornwall, a citizen of the United States of America, residing at Pelham Manor, county of Westchester, State of New York, have invented a new, original, and ornamental Design for a Combined Ash Tray and Humidor, of which the following is a specification, reference being made to the accompanying drawing, forming a part thereof.

Fig. 1 is a front elevational view of a combined

ash tray and humidor embodying my new design;

Fig. 2 is a top-plan view thereof; and
Fig. 3 is a sectional view on lines 3—3 of
Fig. 2.

I claim:

The ornamental design for a combined ash tray and humidor, substantially as shown.

HAMILTON O. CORNWALL.
